UNITED STATES PATENT OFFICE.

EUGENE A. KUEN, OF CINCINNATI, OHIO, ASSIGNOR TO THE THOS. J. CORCORAN LAMP COMPANY, OF CINCINNATI, OHIO, A CORPORATION OF OHIO.

ELECTRIC CONNECTER.

Application filed May 24, 1920. Serial No. 383,909.

To all whom it may concern:

Be it known that I, EUGENE A. KUEN, a citizen of the United States, residing in Cincinnati, in the county of Hamilton and State 5 of Ohio, have invented certain new and useful Improvements in Electric Connecters, of which the following is a specification.

My invention relates to electric connecters having two terminal posts. It is the object 10 of my invention to provide novel means whereby to maintain the lateral relations between the posts, and between the posts and the tube, to prevent short-circuiting between them; and, further, to provide novel means 15 whereby ready assembling of the parts is obtained; and the invention will be further readily understood from the following description and claim, and from the drawings, in which latter:

20 Fig. 1 represents a side elevation of a connector, partly broken away, embodying my invention.

Fig. 2 is an edge elevation of the same.

25 Fig. 3 is a rear end elevation of the same.

Fig. 4 is a front end elevation of the same.

Fig. 5 is a longitudinal axial-section of the same, taken on the line 5—5 of Fig. 1;

Fig. 6 is a cross-section of the same, taken on the line 6—6 of Fig. 1.

30 Fig. 7 is a cross-section of the same, taken on the line 7—7 of Fig. 4; and

Fig. 8 is a cross-section of the same, taken in the plane of the line 8—8 of Fig. 7.

35 My improved device is especially applicable in connection with connecters used for electric lamps employing electric lamp bulbs having two end-terminals, and used as headlights, spot-lights, and the like, for automobiles and other vehicles. Such a bulb is 40 exemplified at 11, having the end-terminals 12, 13, which connect with the filament of the lamp.

45 The connecter comprises a tube 15, which is adapted to be received and positioned in usual manner in a usual cylindrical flange at the rear end of the reflector of the lamp. The plug 16 of the electric light bulb is received in the end of the tube, and has suitable mechanical connection therewith, instanced as a pin and bayonet connection slot 17.

50 An insulating block or washer 21, shown as a comparatively thin washer, for instance of insulating fibre, is fixed in the tube, in suitable manner, as by means of indenting

the body of the tube with inwardly extending prongs 22, against which one end of the washer is received, and prongs 23 bent against the other end of the washer, for positioning the washer endwise in the tube. 60 My invention is especially useful when employing thin fibre washers which, in practice, are comparatively inexpensive, and aid in maintaining the terminal posts in proper relation to the washer, to each other, and to 65 the tube.

Terminal posts 25, 26, are received through the washer. Each of the posts comprise a sleeve 27, which is provided with an annular shoulder 28 and a peripheral seat 29, which 70 latter is preferably of greater diameter than the diameter of the outer end 30 of the sleeve. A plunger 33 is located in the sleeve and projects therefrom. A spring 31 is located between the bottom end of the bore 32 in the 75 sleeve and the plunger. The plunger is provided with an inner annular shoulder 34, arranged to contact an annular flange 35 at the outer end of the bore, forming a stop for the outward movement of the plunger, this stop 80 being formed by spinning or upsetting the outer edge of the wall of the bore after the plunger has been placed in the bore.

The insulating washer is provided with 85 holes 39, into which the ends of the terminal posts are received, the posts being forced into these holes so that the peripheral seats 29 make firm contact with the walls of the holes, with the shoulders 28 bearing against one end of the washer. 90

The outer end of each of the sleeves is provided with a transverse hole 41. An electric conductor 42 is provided with an insulating covering 43. The insulating covering, which is preferably a woven tubular fabric, is removed from the extreme end of the electric conductor, so as to electrically expose this end. The electric conductor is preferably a number of fine wires twisted or woven together. 95

A ferrule 45, of electro-conductive metal, comprises a tubular portion 46, and a cup-portion 47, having an inner annular shoulder 48 between them. The outer end of the cup-portion is preferably curled outwardly, as shown at 49, to form an outwardly flaring annular flange. The electric conductor is arranged to be passed through the tubular portion, with the end of the insulating covering impinging against the shoulder, so as 100 105 110

to position the same endwise, for positioning the electric conducting wire in the tubular portion and the insulating covering in the cup-portion.

5 The tubular portion is inserted in the transverse hole in the terminal post, the outer annular shoulder 51 at the end of the tubular portion impinging against the side of the terminal post. The outer end of the 10 electric conductor is bent across the outer end of the tubular portion and the opposite face of the terminal post, and across the end of the terminal post, where the end of the wire or wires are soldered to the end of the 15 terminal post by a suitable solder, shown at 52. This positions the end of the insulating material within the ferrule, and fixes the 20 endwise relation between the electric conductor, the insulating material, the ferrule, and the post. It further insures excellent 25 electric connection between the electric conductor and the terminal post. The ferrule aids in directing flexure of and in supporting the electric conductor and insulating material, for preventing abrupt bends therein, distinctly aided by the outwardly curved flanged end of the cup-portion.

An insulating plate 55 is provided with holes 56, in which the ferrules are located, 30 for positioning the ferrules with relation to each other, and controlling the relative positions of the ferrules, the insulating posts, and the tube. The insulating plate forms a 35 positioning clip, and acts in connection with the insulating washer to maintain the terminal posts in parallel relation to prevent short-circuiting between them, and prevents the ferrules, as well as the inner ends and the outer ends of the terminal posts, from 40 moving either toward or from each other re-

spectively, and prevents short-circuiting between the ferrules, between the posts, and between the posts and the tube. The ferrules may be comparatively loose in the positioning plate or clip, for aiding in ready 45 assembling of the parts, but the connection is preferably firm. The positioning plate is separate from the insulating washer, and is shown at substantial right angles thereto. The parts are of simple construction and are 50 readily and conveniently assembled.

Having thus fully described my invention, what I claim as new and desire to secure by Letters Patent, is:

In an electric connector, the combination 55 of a supporting tube, an insulating body in said tube, a pair of electric terminal posts in said insulating body, said terminal posts provided with projections extending from said insulating body outside said tube, electric conductors secured to said projections and extending at substantial right angles therefrom, and an insulating plate independent of said insulating body and distanced therefrom, said insulating plate provided with spaced-apart holes, said insulating plate extending in a plane which is substantially parallel with the single plane in which the longitudinal axes of both said 60 projections extend, and said electric conductors located in said holes, whereby said electric conductors and said projections are held in spaced-apart relations.

In testimony whereof, I have hereunto signed my name in the presence of two sub- 75 scribing witnesses.

EUGENE A. KUEN.

Witnesses:

JAMES J. FITZPATRICK,
DELMA WERNING.
